UNITED STATES PATENT OFFICE.

CAMILLE DREYFUS, OF BASEL, SWITZERLAND, ASSIGNOR TO CELANESE CORPORATION OF AMERICA, A CORPORATION OF DELAWARE.

MANUFACTURE OF TEXTILES.

No Drawing.

Application filed December 22, 1921. Serial No. 524,276.

This invention relates to the manufacture of woven, knitted or other textile fabrics. When cotton or other suitable yarn finished in the ordinary way is used for weaving, knitting or other textile purposes, and the article is exposed to water, in most cases the article gets fluffy and so loses its appearance, due to the fact that by the action of water the finish is softened or is loosened or 10 disappears. Articles made with yarns so finished, or the yarns themselves, have to be singed or otherwise treated in order to improve their appearance.

I have now found that by using a yarn 15 which has been impregnated with a permanent finish by treatment with an acetate of cellulose solution for the manufacture of fabrics, ribbons, or textiles, or articles, the article into which it is woven, or the yarn 20 itself, can be exposed to water treatment without losing its appearance and without getting fluffy. Instead of using yarn treated with cellulose acetate solution, I can use 25 yarns treated with solution of other organic cellulose esters or ethers (hereinafter included in the term organic derivatives of cellulose), to create a permanent impregnation or finish in cotton yarns or other suitable yarns. For instance, if cotton yarn so 30 treated with a permanent finish is woven together with silk in a ribbon, this mixed silk cotton ribbon can be dyed or otherwise be exposed to water without spoiling the appearance of the ribbon, whilst if in such case a cotton yarn is used containing a finish that was not permanent the appearance of the ribbon is fluffy and generally bad after treatment with water or the like.

It will be understood that the present invention in no way concerns the well known 40 operation of impregnating or "doping" textile fabrics with solutions of cellulose acetate or the like for the purpose of producing taut water proof materials. In such operations the coating preparations are applied 45 to the woven or like fabric after its manufacture, and fill and seal the interstices of the fabric, whereas according to the present invention textile fabrics are woven, knitted or constructed entirely or partly of yarn 50 which has been impregnated with a permanent finish of cellulose acetate or other organic derivatives of cellulose, such yarn being hereinafter in the claiming clauses referred to as individually impregnated 55 yarn.

What I claim and desire to secure by Letters Patent is:

1. Textile fabrics comprising yarn individually impregnated with a permanent finish of an organic derivative of cellulose. 60
2. Textile fabrics comprising cotton yarn individually impregnated with a permanent finish of an organic derivative of cellulose. 65
3. Textile fabrics comprising yarn individually impregnated with a permanent finish of cellulose acetate. 65
4. Textile fabrics comprising cotton yarn individually impregnated with a permanent finish of cellulose acetate. 70
5. Textile fabrics consisting of cotton yarn impregnated with a permanent finish of cellulose acetate, and of silk yarns unimpregnated with said permanent finish.

CAMILLE DREYFUS.
